UNITED STATES PATENT OFFICE

2,257,593

COLLAR

Richard C. Campbell, North Plainfield, N. J.

Application June 10, 1939, Serial No. 278,387

2 Claims.

(CL. 2—131)

This invention relates to collars and has for an object to provide means for making the fold line thereof permanent.

Another object of the invention is to provide an improved construction of collar which may be used as a separate collar structure of the fold over type or an attached collar of the same type.

This type of collar consists of a cape portion and a band portion, with the cape folding over the band at the junction of the two parts along what is known as the "fold line arc."

It is common knowledge that in collars as made today, it is possible in production to position the "fold line arc" as desired, but no means has been found to make it permanent and prevent its distortion in repeated launderings.

In collars such as described in Patents Nos. 2,033,680 and 2,033,681 a fold line is provided that makes it possible to readily shape the collar but the object of this invention is, not only to provide a definite line of fold but a means of making it permanent.

It will be found with the use of the permanent finished lining in the band portion of the collar and the application of the beading along the entire length of the fold line arc, there is established a definite fold line and a means of supporting it.

In the accompanying drawing—

Fig. 1 is an elevation of a collar embodying the invention, certain parts being broken away for better illustrating the construction;

Fig. 2 is an elevation of the cape interlining of the collar shown in Fig. 1;

Fig. 3 is an illustration of the band interlining of the collar shown in Fig. 1;

Fig. 4 is an elevation of a pleated or braided web having a beaded edge adapted to be used along the upper edge of the band interlining;

Fig. 5 is a fragmentary view of the left-hand end of the structure shown in Figs. 1 to 4 inclusive, and illustrating how they are connected together;

Fig. 6 is a view similar to Fig. 5 but showing the outer finished plies stitched to the cape and band interlinings;

Fig. 7 is an enlarged sectional view through Fig. 5 approximately on the line 7—7;

Fig. 8 is an enlarged sectional view through Fig. 6 on the line 8—8;

Fig. 9 shows the construction illustrated in Figs. 6 and 8 but turned inside out;

Fig. 10 is a sectional view through Fig. 11 on the line 10—10, the same being on an enlarged scale; and

Fig. 11 is a perspective view of the finished collar.

In carrying out the objects of the invention the cape interlining 1 may be of any desired fabric which is now commonly used for the interlining of collars. The band interlining 2, however, is made from a permanently finished fabric such as described in Patent No. 2,150,825, issued March 14, 1939. This fabric has the characteristic of maintaining its weight and firmness through repeated laundering operations and holds the collar to the original designed shape.

While the permanent finished band lining is wholly responsible for supporting and maintaining the "fold line arc" for the life of the collar, it has been found that the band lining, on account of its stiffness, has a tendency to kink when the collar is shaped.

To overcome this fault, and also to add flexibility to the fold line, it has been necessary to introduce along the entire length of the fold line a "braided" or "pleated" web, well known to the industry for other uses, which has a beading of tube-like construction along one edge, thus producing more flexibility in the fold line.

After the two interlinings have been properly cut or formed they are overlapped, as shown in Fig. 7, and then a braid or pleated web 6 is applied. This web is well known in the trade and is provided with a flat portion 7 and a beaded portion 8 of tubular construction along one edge of the flat portion. This braid or web is arranged as shown in Fig. 7 and then the respective lines of stitching 9 and 10 are applied for securing all the parts together, placing the "fold line arc" entirely within the cape portion, causing the collar to fold slightly above the neckband tabs 16 (see broken line 5, Fig. 1) producing the shoulders which raise the fold line and gives the collar a rolled front.

The beading 8 forms the margin for the lower edge of the fold, all of the fold being disposed above this point and entirely within the cape portion and above the upper edge of the neckband tabs.

After this has been done, the outer plies 11 and 12 are laid on the rear face of the combined structure just described so that the parts will appear as shown in Fig. 8. A line of stitching 13 is provided along the top and ends of the combined structure, after which the combined structure is turned inside out so that the parts will appear as illustrated in Fig. 9. After this has been done, a line of stitching 14 is provided across the top and ends of the structure and lines of

stitching 18' at the center. The lower edge 15 of the combined structure is left unstitched where the collar is to be attached, but where it is to be detachable the lower edge may be turned in or folded over to produce a finished structure. When the parts are folded as shown in Fig. 10, the outer and inner parts of ply 11 form finished surfaces 3 and 4 as shown in Fig. 11.

I claim:

1. A fold-over collar comprising a cape portion and a neckband portion, the said collar being formed of outer plies and an interlining therebetween, the interlining comprising a cape portion and a neckband portion, the upper edge of the neckband interlining overlapping the lower edge of the cape portion interlining, stitching for sewing said overlapping portions of the interlining together and a flexible web member secured to the overlapping portions of the interlining and formed with a beading along one edge which is positioned at the level with the upper edge of the neckband interlining, said beading being of greater thickness throughout its length than the web portion for spacing the cape portion outwardly of the neckband portion and for defining the lower marginal edge of the fold of the collar so that the fold line over which the collar folds is positioned within the cape portion.

5 of the collar, the cape portion being folded directly over the beading which projects toward the folded-over cape portion and which provides substantially a line-contact with said cape portion.

2. A fold-over collar comprising a cape portion and a neckband portion having neckband tabs projecting from the two ends thereof, the said collar being formed of outer plies and an interlining therebetween, the interlining comprising a cape portion and a neckband portion also having neckband tabs projecting from the two ends thereof, the intermediate portion of the neckband interlining between the neckband tabs extending above the upper edge of the neckband tabs and being positioned so as to overlap the lower edge of the cape portion interlining, stitching for securing said overlapping portions of the interlining together and a flexible web member secured to the overlapping portions of the interlining and formed with a beading along one edge which is positioned adjacent the upper edge of the neckband interlining to define the lower marginal edge of the fold of the collar so that the fold line over which the collar folds is positioned within the cape portion of the collar above the upper edge of the neckband tabs.

RICHARD C. CAMPBELL.
